UNITED STATES PATENT OFFICE

2,156,575

APPARATUS FOR GRAVITATIONALLY SEPARATING AND CLEANING COAL AND THE LIKE

Earl Stump, Chicago, Ill., assignor to Roberts and Schaefer Company, Chicago, Ill., a corporation of Illinois

Application September 22, 1937, Serial No. 165,130

5 Claims. (Cl. 209—475)

My invention relates to improvements in means for gravitationally separating and cleaning coal and the like and is adapted to make use of air as a cleaning and gravitationally supporting medium whereby heavy and light materials may be stratified and separated.

Among the objects of my invention are to provide a new and improved form of air separating or air washing apparatus. It will be understood that while I have illustrated my device as applied to an apparatus primarily adapted for treatment of coal by air and while I have used the terms "coal" and "air" in the specification and claims, it is understood that these terms are used as illustrative only and that any solids which can be classified or treated by gravity may be treated by my apparatus and any suitable gas may be used.

My invention is illustrated more or less diagrammatically in the accompanying drawings, wherein—

- 20 Figure 1 is a side elevation;
 Figure 2 is a longitudinal section;
 Figure 3 is a section along the line 3—3 of Figure 1.

25 Like parts are indicated by like characters throughout the specification and drawings.

This application shows a modification of the structure shown in my co-pending application Serial No. 733,053, filed June 2, 1934.

- 30 1 is a supporting frame. It carries a plurality of uprights 2, 3, 4 and 5. Between the uprights 3 and 4, is a housing which contains an air box 6. This air box receives a pulsating current of air under pressure from the blower 1, which discharges the air through a manually adjustable valve housing 8, a pulsating valve housing 9 and a pipe 10. 11 is a manually adjusted valve having a valve handle 12, working on a quadrant 13 adapted to be fixed in position by the thumb screw 14. 15 is a pulsating valve mounted for rotation on a valve shaft 16, driven by a pulley 17 and belt 18 from any suitable source of power, preferably the same source of power as the blower. Both these valves are butterfly valves. The manual valve is set manually to control the total volume of air which may reach the air box. The pulsating valve rotates and alternately opens and closes the effective area of the air passage to control the air in a series of pulsations. The air box is closed by a marble pack which comprises a lower perforate plate 19, an upper perforate plate 20 and a mass of marbles or marble-like objects 21 which are held together under some pressure within the pack and furnish a resistance to the passage of air upwardly from the air chamber 6.

The perforate plate 20 forms a floor for the downwardly inclined coal chute or trough 22, having side walls 23, and also supported on the uprights 3 and 4. 24 is a feed platform supported on the uprights 2 and 3. It carries a feed box 25 closed at the bottom by a reciprocating feed plate 26 adapted to travel on rollers 27 and to be reciprocated by a crank 28, driven by a sprocket 29 and chain 30 from the sprocket 31 on the flutter valve shaft. Crank 28 is connected to the feed plate by a connecting rod 32, and a reciprocating stem 33. This feed box receives coal from the hopper 34 and a manually adjusted valve 35 is provided to cooperate with the reciprocating member to control the rate of flow to the separating trough or chute. The feed plate is spaced above the floor of the trough. The coal lies in the trough generally as indicated at 36 so that there is always a gradient for the coal to flow down from the feed plate to the trough. The pulsating current of air passing up through the coal bed agitates the coal. There is no mechanical agitation but this agitation or pulsation effect of the current of air is sufficient to permit the coal to flow freely under the influence of gravity down along the floor of the trough being stratified into three zones so that the heavy material or refuse lies at the bottom, the light material or coal at the top with an intermediate middling zone between them.

37 is a distribution plate. It is immersed in the bed of coal in the trough being held substantially parallel to the floor of the trough by hangers 38 carried on the walls of the trough at a point well above its floor. This plate may take the form of a screen or grid or perforate plate as the case may be. In any event the perforations are much larger than the maximum size of coal particles to be treated so that the coal may pass freely upwardly through this plate and refuse may pass freely downwardly through the plate and the plate is preferably so positioned as to tend to define the boundary between the middling zone and the coal zone. This plate is reciprocated by means of a link 39, lever 40 and link 41, the link 41 being pivoted at one end to the reciprocating feed plate 42 and being provided with a turn buckle 43. The point of attachment of link 39 to lever 40 is adjustable, as indicated at 44, so that the distance through which the distribution plate is reciprocated, or its stroke, may be increased or diminished.

44 is a discharge housing in communication with the end of the trough. Pivoted in that housing is a sloping middlings trough, floor plate 45 which may be manually adjusted in position by 55

the operator and locked in position by means of the thumb screw 46, the purpose of this being to raise or lower the horizontal edge of this floor plate because it defines the upward boundary of 5 the refuse stream, the refuse passing down from the floor of the trough beneath this plate where it is controlled by a gate 47. 48 is the coal chute floor plate. It is presented to the stream of coal in much the same way as the plate 45 is presented 10 to the stream of refuse. The space between 45 and 48 is the middlings chute and this middlings chute may be controlled by a gate 49. The coal passes over the plate 48 and is discharged without further interference through a chute 50. Middlings 15 leave the apparatus through a chute 51 and refuse through a chute 52 as indicated. The pivoted coal plate 48 is supported at its upper end on the outward end of the distribution plate 37 and is held by gravity against it so that as the 20 feed plate is reciprocated causing reciprocation of the distribution plate, the distribution plate causes a slight rocking movement of the coal plate 48, thus opening and closing slightly the middlings chute and so avoiding clogging in the middlings 25 area and also avoiding the danger of large pieces of coal straddling the edge of the coal chute, and so interfering with the flow of material.

The gates 47 and 49 are controlled by levers 30 53, 54, and links 55 and 56. The mechanism for controlling these links and levers and controlling the gates forms no part of the present invention and is not here illustrated or described. Suffice it to say that these gates are ordinarily slightly open but may open wider or less wide as the case 35 may be either by manual control or by automatic control.

I claim:

1. In a coal treating apparatus, a floor along 40 which coal is adapted to travel, a distribution plate immersed in the stream of flowing coal, means for reciprocating said plate to agitate the coal as it travels along the floor to cause gravitational separation of the coal into generally horizontal strata, a chute at the discharge edge of 45 the floor having a horizontal cutting edge presented to the oncoming current of coal, and means for imparting a vertical vibratory movement to said cutting edge, said last means comprising a connection between the said chute and 50 plate whereby the cutting edge and plate move in unison.

2. In a coal treating apparatus, a floor along which coal is adapted to travel, a distribution plate immersed in the stream of flowing coal,

means for reciprocating said plate to agitate the coal as it travels along the floor to cause gravitational separation of the coal into generally horizontal strata, a chute at the discharge edge of the floor having a horizontal cutting edge 5 presented to the oncoming current of coal, means pivoting said chute on a horizontal axis at a point remote from the cutting edge, and means for imparting to the chute a vibratory movement about its pivot axis, said last means comprising 10 a connection between the chute and said plate whereby they move in unison.

3. In a coal treating apparatus, a floor along which coal is adapted to travel, a distribution plate immersed in the stream of flowing coal, 15 means for reciprocating said plate to agitate the coal as it travels along the floor to cause gravitational separation of the coal into generally horizontal strata, a chute at the discharge edge of said floor having a horizontal cutting edge 20 presented to the oncoming current of coal, a discharge passage having an opening beneath said cutting edge, and means for expanding and contracting the cross-sectional area of said passage, 25 said means comprising a connection between the distribution plate and said chute, whereby the cutting edge of the chute is vibrated vertically in unison with the movement of the distribution plate.

4. In a coal treating apparatus, an inclined deck down which coal is adapted to travel, a stirring member suspended parallel to the deck and immersed in the stream of flowing coal, means for reciprocating said member to agitate the coal as it travels down the deck, an inclined chute supported at its upper end on said stirring member and having a horizontal cutting edge presented to the oncoming current of coal, and means for pivotally supporting said chute at its lower end, whereby movement of said stirring member imparts movement to the cutting edge of said chute.

5. In a coal treating apparatus, an inclined deck down which coal is adapted to travel, a stirring member suspended parallel to the deck and immersed in the stream of flowing coal, means for reciprocating said member to agitate the coal as it travels down the deck, a discharge passage at the lower end of the deck, and means supported in part on said stirring member and operated thereby for increasing and decreasing the size of said discharge passage in unison with the reciprocating movement of said member.

EARL STUMP.
